R. V. FITZ GERALD

TRANSMISSION BRAKE

Filed June 6, 1923

Inventor

RAYMOND V. FITZ GERALD
By his Attorneys
Philip Dunn, Reis & Stearns

UNITED STATES PATENT OFFICE.

RAYMOND V. FITZ GERALD, OF EASTON, PENNSYLVANIA, ASSIGNOR OF ONE-HALF TO
WILLIAM P. FITZ GERALD, OF PHILLIPSBURG, NEW JERSEY.

TRANSMISSION BRAKE.

Application filed June 6, 1923. Serial No. 643,624.

To all whom it may concern:

Be it known that I, RAYMOND V. FITZ GERALD, a citizen of the United States, residing at Easton, county of Northampton, 5 and State of Pennsylvania, have invented certain new and useful Improvements in Transmission Brakes, fully described and represented in the following specification and the accompanying drawings, forming 10 a part of same.

This invention relates to certain improvements in brake or transmission bands for automobiles, and particularly for the transmission bands of Ford automobiles.

15 In the well known Ford type of car the transmission drum is mounted in a two-part casing and the transmission bands are loosened or tightened on the drums by means of spring rods connected with the bands and 20 passing through the casing, the rods being operated from suitable levers or pedals located outside the casing.

When it is necessary to reline these bands or to get them out for any other desired reason, it has been necessary to take off the 25 top of the casing, disconnect the rods and springs, and then take the bands out. This is a slow tedious operation, taking considerable time.

30 It has been proposed to provide a band having an ear or lug which can be removed by the insertion of a suitable tool inside the casing, to make it unnecessary to take the casing down to get at the bands and 35 drums. In these proposed structures, however, it has been usually necessary to disconnect the rods from their operating mechanism and remove them before the cars and bands could be removed from the transmission casing.

40 It is the especial object of the present invention to provide a brake or transmission band having a removable ear or ears so formed and arranged that the ear may be removed from the band and from the rod without it being necessary to take down or disconnect the rod or casing in any way. 45 It is a further object of the invention to provide an improved removable ear which 50 can be readily snapped into position on the band and in which end play with respect

to the band is prevented by either a pull or push on the ear.

It is a further object of the invention to provide an ear which can be conveniently 55 and cheaply made, the ears being so formed that they can be made at the same casting and used on opposite ends of the bands.

With these and other objects not specifically referred to, the invention consists 60 in certain novel parts, arrangements and combinations, which will be fully described in connection with the accompanying drawing, and the novel features then pointed out in the claims hereunto annexed. 65

Referring to these drawings—

Figure 1 is a sectional elevation of a transmission casing and its drum, brake band, and operating rod therefor, embodying the novel features of the invention. 70

Figure 2 is a perspective view of the band.

Figure 3 is a face view on an enlarged scale and partly in section of the improved band and associated ear.

Figure 4 is a section taken on line 4—4 of 75 Fig. 3.

Referring now to these drawings, the construction which has been chosen to illustrate the invention is the transmission drum of an automobile of the Ford type. It will be understood that as to certain features the invention can and is intended to be used in other relations.

In the drawings the transmission drum 1 is mounted on a shaft 2, these parts being 85 positioned in a casing which includes a lower part 3 and an upper part 4, these parts being provided with co-operating flanges 5 secured together by bolts 6. The upper part of this casing is closed by a removable cap 80 80 plate 7.

Encircling the drum is a transmission band 8. This transmission band is a flexible band, such as a steel band and is provided as usual with a friction lining 9. This band is 95 a split band, as usual, and encircles the drum, and this band is tightened or loosened on the drum by means of a rod 10 which takes bearing in a sleeve 11 passing through the wall of the upper part 4 of the casing, 100 the rod being operated by any suitable lever mechanism, indicated at 12.

This rod takes through a pair of projections or ears indicated by the numeral 13, these ears forming an important feature of the invention. While these ears may be formed in various ways, they will be so constructed and arranged that they may be removed sideways from the operating rod 10 so that it is unnecessary to take out the rod 10 or disassociate it with its actuating mechanism. Furthermore, these ears will be so associated with the band that any end play in either direction relatively to the band is prevented, and these ears will also be so secured in position that one or both of them may be readily removed from the band by a suitable tool, as a screw driver.

In the best constructions both ears are made removable. As shown, the band is provided at or near the edge of its open ends 20 with a pair of holding projections 14, 15 conveniently formed by pressing in the metal of the band, and the lower projection is formed with a recess 16 facing toward the end of the band. The bands at their ends 25 are provided with stops conveniently produced by turning over the end of the metal of the band, as indicated at 17. The improved ear or ear members are shown as including an ear proper marked 13 rising 30 from a base 19, these parts being preferably integral. The ears 13 are formed with slots 20 which are generally T-shaped with the stem of the T opening sidewise of the projection, as indicated at 21 in Figs. 2 and 3. 35 The ends of the head of the T form recesses for holding the rod when the ears are in cooperative relation therewith.

The bases are provided with a slot 22 which fits over the upper projection 14 on 40 the band and the end of the base is cut away at each side to form a tab 23 which fits into the socket 16, before referred to.

With this construction the ears are held firmly in position on the band against end 45 play and by lifting, through a suitable tool, from the band the ear may be removed sideways and thus free the rod. The ears are easily accessible by simply removing the cover plate 7 from the transmission casing 50 and after the ear or ears are removed from the band the band may be readily withdrawn from the casing.

In the best constructions the ears are 55 spring seated on the band, that is, a construction is adopted by which the members may be snapped in position and held with sufficient firmness so that the movement of the rod does not loosen them from the plate, and spring means is provided by the invention for accomplishing this.

In the particular construction illustrated there is secured to the band, as by rivets or in any other suitable manner, a spring plate 24, this plate having spring ears 25 between 65 which the upper end of the base may be

sprung, these ears being formed with projections 26 adapted to extend into recesses 27 formed in the sides of the bases 19, before referred to, this plate 24 being located preferably just to the rear of the end stop 70 17, before referred to.

In the assemblage of the parts preferably the side recesses 21 in the ears face toward opposite sides of the band so that the same casting may be arranged for the parts at 75 each end of the band.

With the construction as shown and described, a very simple and efficient securing device for the transmission or brake bands has been provided, and one in which 80 the band may be removed from its associated mechanism without dismantling the latter in any way and one which can be simply and cheaply made and assembled. While the invention has been shown and 85 described in its preferred form, it will be understood that various changes may be made in the specific structure described without departing from the scope of the invention as defined in the appended claims. 90

What I claim is:

1. In a brake or transmission band, the combination with a drum, of a flexible band encircling the drum, a rod for operating the band, ears on the ends of the band, said ears being provided with rod receiving slots opening to the side of the band whereby the ears may be removed sidewise from the rod, and means for removably locking one of the ears to the band. 95

2. In a brake or transmission band, the combination with a drum, of a flexible band encircling the drum, a rod for operating the band, ears on the ends of the band, said ears having rod receiving slots opening to the side of the band whereby the ears may be removed sidewise from the rod, means for 105 removably locking one of the ears to the band, and means for preventing end play between the removable ear and the band in 110 either direction.

3. In a brake or transmission band, the combination with a drum, of a flexible band encircling the drum, a rod for operating the band, end stops on the ends of the band, upper and lower projections on the band, ears having bases positioned on the ends of the band, slots in the bases into which the upper projections enter, tabs on the bases entering the lower projections whereby the 120 bases are removably secured on the band, said ears having rod receiving slots opening to the side of the band. 115

4. In a brake or transmission band, the combination with a drum, of a flexible band encircling the drum, a rod for operating the band, end stops on the ends of the band, raised sockets on the band, ears having bases positioned on the band between the end stops and the sockets and having tabs pro- 125 130

jecting into the latter, said ears having rod receiving slots, and spring members on the sides of the band between which the ears may be sprung for removably locking them 5 in place.

5. An ear for transmission or brake bands including a base and means for removably securing it to a band, the ear having a rod receiving slot opening sidewise thereof.

6. An ear for transmission or brake bands 10 including a base and means for removably securing it to a band, said ear rising from the base and having a slot provided with an opening sidewise thereof and rod receiving recesses at each side of the opening. 15

In testimony whereof, I have hereunto set my hand.

RAYMOND V. FITZ GERALD.
